UNITED STATES PATENT OFFICE.

ANDREW B. HENDRYX, OF NEW HAVEN, CONNECTICUT, ASSIGNOR TO
THE A. B. HENDRYX COMPANY, OF SAME PLACE.

DESIGN FOR A PLATE FOR FLOWER-POT BRACKETS.

SPECIFICATION forming part of Design No. 28,377, dated March 15, 1898.

Application filed February 8, 1898. Serial No. 669,590. Term of patent 14 years.

To all whom it may concern:

Be it known that I, ANDREW B. HENDRYX, of New Haven, in the county of New Haven and State of Connecticut, have invented a new Design for a Plate for Flower-Pot Brackets; and I do hereby declare the following, when taken in connection with the accompanying drawings and the letters of reference marked thereon, to be a full, clear, and exact description of the same, and which said drawings constitute part of this specification, and represent, in—

Figure 1, a plan view of the under face of a bracket-plate embodying my design; Fig. 2, a side view of the same.

This invention relates to a design for a plate for flower-pot brackets; and the design consists in the configuration and ornamentation, as herein shown and described.

As herein shown, the design consists of a 20 circular plate A and centrally-arranged hub B, the under face of the plate being ornamented by radial ribs C, the outer ends of which are rounded, forming a scalloped edge. Upwardly from the edge of the plate projects 25 a sectional flange formed from a series of closely-arranged scallop-shells D, all as shown in the accompanying illustrations.

I claim—

The design for a plate for flower-pot brackets 30 as herein shown and described.

In testimony whereof I have signed this specification in the presence of two subscribing witnesses.

ANDREW B. HENDRYX.
